UNITED STATES PATENT OFFICE.

EDWARD C. BELL AND RAYMOND S. CASE, OF UNIONVILLE, CONNECTICUT.

PROCESS OF MAKING CARTRIDGE-SHELLS.

1,169,378.

Specification of Letters Patent.

Patented Jan. 25, 1916.

No Drawing.

Application filed August 15, 1914. Serial No. 856,978.

To all whom it may concern:

Be it known that we, EDWARD C. BELL and RAYMOND S. CASE, each a citizen of the United States, residing at Unionville, in the county of Hartford and State of Connecticut, have invented a new and Improved Process of Making Cartridge-Shells, of which the following is a specification.

Our invention relates to the process above set out, and an object of our invention, among others, is to provide a process by means of which cartridge shells of a superior quality may be produced in a particularly efficient manner.

15 In the making of paper shells more particularly used to contain a charge of powder, with or without other material, a tube is generally formed and is then cut up into proper lengths to provide the shells, these 20 short lengths being supplied with the caps and other devices forming the complete shell.

It is desirable that the inner surface of the shells shall be coated with a material, as 25 paraffin, which is of particular advantage in that it prevents the inner surface of the shell from being scorched or burned when the powder is ignited. This paraffin may be applied in the simplest manner, by dipping 30 the shells in baths of melted paraffin, thus treating the outside as well as the inside of the shell. It is also essential that the outside of the shell shall be treated with a water-proof coating in order that it will not be 35 detrimentally affected by changes in atmospheric conditions. It is advisable to apply paraffin to the surface of the paper comprising the tube in as small quantities as possible for the reason that the paraffin injures the fibers of the paper to an extent to 40 weaken the shell to a certain degree, and while the advantages of the paraffin are such as to require its use on the inner surface of the tube we have provided means whereby 45 just a sufficient quantity may be applied to each of the shells to get all of the advantages required and at the same time these quantities will not be exceeded to an extent to injure the shell to a material degree.

50 In carrying out our process a tube is prepared as by rolling up a strip of paper into

several plies and treated with an adhesive, the tube, when completed, being in a moist state. The tube is then thoroughly dried after which it is treated on its outer surface 55 with a water-proofing material so that the cartridges produced therefrom will not be affected by atmospheric conditions to an extent to change their size or characteristics. This water-proofing material need not be 60 confined to any particular composition, but we have found that a water-proofing material comprising the characteristics of the cellulose mixtures will produce satisfactory results. In many instances it is desired that 65 the finished cartridge shall be colored and when such a cartridge is to be produced, the desired coloring matter may be incorporated in the water-proofing material and treated therewith, this water-proofing material effectually preventing the colors from being 70 injuriously affected in the handling of the tubes or shells. After the tubes are thus treated with the water-proofing material, with or without color, they are dipped in a 75 bath of paraffin, having such characteristics that a very thin coating will be applied to the tubes, in fact just enough of the paraffin being applied to provide the qualities required on the inner surface of the shell. The 80 outer surface of the shell being treated with the water-proofing material, the paraffin will not penetrate the paper composing this surface of the shell. The water-proofing material, when mixed with color, also now effects another purpose, and that is, it prevents the color from running under the influence of the hot moist paraffin.

We claim—

1. The process of making a cartridge tube 90 that consists in forming the tube from paper by rolling several plies one upon another, drying out the tube, then treating the completed tube with a water-proofing material, and then treating both its outer and inner 95 surfaces to a coating of paraffin.

2. The process of making a cartridge tube that consists in forming the tube from the proper material by rolling several plies one upon another, then drying out the tube, then 100 treating the completed tube to a water-proofing material with coloring matter form-

ing a part thereof, and then treating both the outer and inner surfaces of said tube to a thin coating of paraffin.

water-proofing material, and then treating the whole tube to a coating of paraffin.

EDWARD C. BELL.
RAYMOND S. CASE.

3. The process of making a cartridge tube that consists in forming the tube by rolling several plies of paper one upon another, then treating the outside of the tube with a
